CARL SHORTAU, OF NEW YORK, N. Y., ASSIGNOR TO T. W. BRACHER,
OF NEW YORK CITY.

Letters Patent No. 66,896, dated July 16, 1867.

IMPROVED WIRE-TWISTING MACHINE.

The Schedule referred to in these Letters Patent and making part of the same.

TO ALL WHOM IT MAY CONCERN:

Be it known that I, CARL SHORTAU, of the city, county, and State of New York, have invented a new and improved Machine for Twisting Metallic Wires or Bands; and I do hereby declare that the following is a full, clear, and exact description thereof, which will enable others skilled in the art to make and use the same, reference being had to the accompanying drawings, forming part of this specification.

The present invention relates to a machine for imparting a twist to metallic wires or bands, and is intended more especially for use in connection with metallic bands employed in the manufacture of that class of hats known as the "Resorte Hats," the invention consisting in a novel and simple manner of imparting such twist to the bands, by means of mechanical devices, as will be hereinafter fully described, reference being had to the accompanying plate of drawings, in which—

Figure 1 is a plan or top view of the machine, and

Figure 2 a transverse vertical section taken in the plane of the line $x x$, fig. 1.

Similar letters of reference indicate like parts.

A, in the drawings, represents the framework of the machine, which consists of a bed-piece, B, supported at each end upon parallel uprights C. D and E, uprights or standards secured to upper side of bed-piece B at each end and at the centre of the same respectively, the three being suitably formed to grasp and hold a metal wire or band, if stretched from one end upright to the other, both at its ends and centre. Upon each side of the centre upright E, and intermediate between it and the end-uprights, puppets, or standards G are secured to the upper side of bed-piece B. H, pinion or gear-wheels, hung in the upper end of puppets G, so as to freely turn; and I, sector-shaped gear-wheels, attached to a horizontal rock-shaft, J, hung in bearings of the posts K of the bed-piece, which sector-gears interlock or engage with the pinion-wheels H. L, a crank-arm, secured to rock-shaft J, to the outer end of which is hung a connecting-rod or wire, M, that, at its lower end, is fastened to a treadle-lever, N, hung to the framework A below the bed-piece B, and in suitable position for being worked or operated by the foot. O, a spiral spring, secured at one end to crank-arm P of rock-shaft, and at its other fastened to the bed-piece B—this spring being provided to throw back the rock-shaft, after having been turned or operated by depressing the treadle-lever N. The pinion or gear-wheels H are slotted in radial lines with their centres for the purpose of receiving the band stretched across from one end-upright to the other, as shown in the drawings.

A metal band having been stretched across from one end-upright to the other of the bed-piece, and therein secured in connection with the centre-upright and slotted pinions, if then the treadle be depressed; the pinions will be made to revolve through the sector-shaped gear interlocking with them, and thus to necessarily twist the band. The band is then taken out, after which, releasing the foot from the treadle, the pinions are thrown back to their original positions.

I claim as new, and desire to secure by Letters Patent—

The construction and arrangement of the slotted standards D, and standards G upon the bed-piece B, slotted pinions H, sector-shaped gear-wheels I, attached to the rock-shaft J hung in bearings K, crank-arms L P, spring O, wire M, and treadle N, substantially as described for the purpose specified.

The above specification of my invention signed by me this twenty-seventh day of November, A. D. 1866.

CARL SHORTAU.
